CLAIM

The ornamental design for a cash cartridge for an automated banking machine, substantially as shown and described.

DESCRIPTION

FIG. 1 is a perspective view showing the first stage of the process.

time series showing a

FIG. 1 is a perspective view showing the front, top, and right side of our new design of a cash cartridge for an automated banking machine.

FIG. 2 is a perspective view
bottom thereof.

FIG. 3 is a front view thereof.

FIG. 3 is a front view thereof.
FIG. 4 is a top view thereof.

FIG. 4 is a top view thereof.
FIG. 5 is a left side view thereof.
The stippling is partially shown on the translucent cover for convenience of the illustration, it being understood that the stippling is continuous over the areas indicated.
